UNITED STATES PATENT OFFICE.

WILLIAM DIETER, OF BROOKLYN, NEW YORK, ASSIGNOR TO VITTEA DEVELOPMENT CORPORATION, A CORPORATION OF DELAWARE.

AIR-CHECK VALVE FOR AUTOMOBILE TORPEDOES.

Application filed June 19, 1920. Serial No. 390,163.

To all whom it may concern:

Be it known that I, WILLIAM DIETER, a citizen of the United States of America, residing in the borough of Brooklyn, county of Kings, city and State of New York, have invented certain new and useful Improvements in Air-Check Valves for Automobile Torpedoes, of which the following is a specification.

10 This invention provides an improved valve for normally closing the air inlet to the alcohol and water vessels of a torpedo, and automatically turning on air to these vessels upon the launching of the torpedo in 15 order to feed air under moderate pressure above the liquids in these vessels, whereby to cause a flow of the alcohol and water to the superheater.

Valves for this purpose are set forth in 20 patent of F. M. Leavitt, No. 1,022,486, dated April 9, 1912, and in patent to W. Dieter, No. 1,319,992, dated October 28, 1919. The present invention provides an improvement upon the constructions set forth in said 25 patents.

The nature of the improved construction and its operation will be made clear with reference to the accompanying drawing, which shows the preferred embodiment 30 thereof, and in which—

Figure 1 is a fragmentary vertical longitudinal mid-section of the mid-portion of a torpedo, certain parts being arranged to illustrate diagrammatically the pipe connections;

Fig. 2 is a vertical mid-section of the air valve on a larger scale, showing the valve in its normal closed position;

Fig. 3 is a similar section showing the 40 valve open;

Fig. 4 is a fragmentary section showing the valve in the position in which it discharges air from the water vessel.

Referring first to Fig. 1, A indicates the 45 shell or hull of the torpedo, and B a reservoir or flask of compressed air with its separable head B' of usual construction. From this head an outlet pipe a leads to a pressure-reducing valve C by which the air 50 pressure in the flask is reduced to a lower and uniform pressure, being the working pressure at which the air is fed to the engine or turbine. From the low pressure side of this valve leads a pipe b which extends to

the heater or superheater D, and from the 55 latter to pipe c which leads to the engine or turbine (not shown) by which the screw propellers are driven in the well-known manner. At some suitable point in the pipe a is introduced any usual starting valve E 60 (shown diagrammatically).

The alcohol and water vessels are commonly constructed in the manner shown, where the outer walls of the air flask are extended rearwardly as a cylindrical portion 65 d having a flange to which is attached a disk or head e constituting thus a container F which is subdivided into two compartments by a partition H of comparatively thin metal which is commonly constructed as an 70 annular vessel having a central opening for the free passage through it of the pipe a, and which is supported within the container F in any suitable manner. The outer compartment I is commonly used to hold water, 75 and the inner compartment J contains the alcohol or other combustible liquid. These liquids are fed over into the superheater D after the opening of the starting valve, by air pressure admitted above the liquids in 80 the vessels I and J respectively. To thus admit air to the tops of these vessels, an air inlet pipe h leads from any convenient point on the low pressure side of the reducer C, as some suitable part of the pipe b. This 85 pipe h admits air to a valve L of novel construction, from which the air flows by pipes k l into the tops of the vessels J and I respectively. From the bottoms of these vessels lead pipes j p which conduct the liquids to 90 valves M and P respectively, from which the alcohol is conducted by pipe j' to the spray nozzle or atomizer n in the superheater D, and the water is conducted by pipe p' to a similar nozzle q in the superheater. 95

So far as described, with the exception of the valve L, all the parts set forth are common, being a part of the standard Bliss-Leavitt torpedo. For convenience, the same letters of reference are used as in the afore- 100 said Patent No. 1,319,992.

Instead of the valves L and K, and relief valve T of that patent, the present invention substitutes the one valve L which will now be described.

This valve comprises an outer casing 6 preferably of elongated cylindrical form having at one end an inlet opening 7, and

105

105

having lateral outlets 8 and 9 discharging respectively into lateral branches 18 and 19 to which the pipes *k* and *l* are coupled. Within the casing or shell 6 is a movable 5 valve or plunger 10 which has a piston portion 11 for closing the outlet 8, and a piston portion 12 for closing the outlet 9. These piston portions make a suitably close fit with cylindrically-bored seat portions 13, 10 14 (Fig. 3) for the outlet 8, and 15 for the outlet 9. Between the piston portions 11 and 12 the valve 10 is externally reduced at 16 to form a neck past which the air may flow. The valve 10 is tubular, being bored out longitudinally for the greater 15 part of its length, but its piston portion 12 is not bored through. Between its inlet end and this piston portion, the reduced or neck portion of the valve plunger is perforated 20 at 17 so that air may flow from its inner bore to reach the outlet 9 when the valve is open, as in Fig. 3.

The valve receives at one end the pressure of a spring 18 which normally presses it to 25 its closed position, as seen in Fig. 2. In this position it is stopped by abutment against a plunger 20 which normally is held seated against a shoulder 21 by the pressure of a spring 22 which is stronger than the 30 spring 18. This spring may react against a shoulder on a bushing 23 screwed into the valve casing and having a central opening for admitting air from the inlet 7. The abutting end of the plunger 20 has an opening 24 of smaller diameter than the bore in the plunger 10, so as to constitute a constriction to the flow of air. The valve plunger 10 has a stem 25 which passes out through the end of the casing opposite to 40 the inlet 7. To prevent leakage, a stuffing box 26 is provided. For convenience of construction, this stuffing box and the recess in which the spring 18 is seated, may be made in a part 60 separate from the remaining 45 portion of the casing 6. The end of the stem 25 is preferably bored out at 27 and screwthreaded, so that a tool or handle may be screwed in, by which to pull open the valve plunger against the stress of the spring 50 18 for testing purposes. While the stem 25 might be rigidly attached to, or integral with, the plunger 10, it is preferable to make it in a separate piece with its end entering within the piston portion 12 and 55 socketed therein, and fastened by a pin 28 with a slight degree of looseness, so that extreme nicety of finish and alignment are not required.

The preferred construction having been 60 thus explained, the operation will now be described:

Normally, or before the torpedo is started, the valve is closed as shown in Fig. 2, the spring 18 holding the valve plunger 10 65 pressed against the abutment afforded by the

plunger 20 which is normally unyielding by reason of its stronger spring 22. When, upon the launching of the torpedo, the air pressure is turned on, the air at working pressure (approximately 400 pounds per square inch) enters through inlet pipe *k* and inlet opening 7, and passes through constriction 24 and into the bore of the plunger 10, and out through perforations 17 as far as the piston portion 12, where it is momentarily checked, but instantly the air pressure displaces the plunger 10 and carries it to the position shown in Fig. 3, so that its piston portion 11 opens wide the outlet 8, and its piston portion 12 passes beyond the seat 15 and opens the outlet 9. This admits air first, or more copiously through outlet 8 and tube *k* to the alcohol chamber *J*; and secondly, or less copiously, through the outlet 9 and tube *l* to the water vessel *I*, thereby establishing air pressures above the liquids in these vessels and instituting the normal outflow of these liquids to the superheater. By reason of the slight check to the flow of air, due to its having to traverse the perforations 17 and flow through the annular space between the seat 15 and the neck 16, the air is slightly retarded in its flow to the water vessel, and its pressure slightly diminished, in order that the alcohol may receive the pressure ahead of the water and thus commence its discharge from the spray nozzle *n* before the water begins to spray from the nozzle *q*, whereby to insure proper ignition of the fuel in the superheater. Any suitable way of constricting or retarding the flow of air to the water vessel, as compared with its admission to the fuel vessel, will suffice to attain this result.

During the normal run of the torpedo the parts remain in the position shown in Fig. 3, the valve plunger 10 being arrested by the seating of its piston 12 against a shoulder or abutment 29 in the casing, the spring 18 being held compressed. At the end of the run, or as soon as the air pressure is spent, the spring 18 presses the valve plunger back to its original position, being stopped by its striking the plunger 20.

It sometimes happens that a pressure of air exists in the water or alcohol vessels which it is desirable to relieve. This may happen by leakage of the highly compressed air in the reservoir *B* through the joint between the reservoir and its head *B'*. Such leakage would be apt to generate a pressure in the water vessel *I* which would collapse the vessel *H*. Whenever any such pressure exists in the vessel *I* materially above the normal pressure therein, this pressure entering through outlet opening 9 acts against the left-hand end of the piston portion 12 (Fig. 2), and upon becoming sufficient to overcome the resistance of the spring 22, this pres-

sure displaces the plunger 10 and spring plunger 20 to the right, as shown in Fig. 4, so that it may escape to the inlet 7 and thence through pipes *h b* through the superheater 5 to the exhaust of the engine. The same movement of the valve plunger opens a vent to the opening 8 communicating with the alcohol vessel, whereby to establish a balance of pressures in the alcohol vessel such as will 10 guard against any collapse of the shell or partition H.

It is customary, in valves of this character, to provide a constriction for momentarily checking the first rush of air when the 15 starting valve is opened, which, if not held back, might burst the alcohol vessel if the pressure therein preponderated, or might collapse this vessel if the pressure in the water vessel were the higher. In the present valve this constriction is provided by the reduced opening 24 in the stop plunger 20.

The valve afforded by the present invention thus performs the several functions required to control the proper admission of 25 air to the alcohol and water vessels upon the starting of the torpedo, while relieving any dangerous pressure that may occur when the torpedo is out of service. These functions are performed by a single valve, thereby simplifying the mechanism, while at the same time affording greater security than heretofore against any abnormal operation.

The invention is not limited to the preferred construction shown, which may be varied to a considerable extent within the scope of the appended claims. The invention is not necessarily limited to the valve having two outlets for supplying air to both 40 alcohol and water vessels. If one vessel were omitted, the outlet corresponding thereto would naturally be omitted or disused.

What I claim is:

1. In a torpedo, in combination with an air inlet pipe and a water and fuel vessel, an intervening air valve comprising a casing having an inlet from said air pipe and outlets to said vessels, and a plunger movable therein, normally closed to shut off said outlets, and movable under air pressure to open the outlets and admit air to said vessels.

2. The combination of claim 1, with a spring normally pressing said plunger to closed position.

3. In a torpedo, in combination with an air inlet pipe and a water and fuel vessel, an intervening air check valve comprising a casing having an inlet and outlet, a plunger mov-

able therein, having a portion closing said outlet, a spring holding the plunger to such closed position, and the plunger movable under air pressure to a position opening said outlet.

4. In a torpedo, in combination with an air inlet pipe and a water and fuel vessel, an intervening air check valve comprising a casing having an inlet and outlet, a valve plunger movable therein, having a piston portion adapted to close said outlet, a spring pressing said plunger to closed position, and said plunger movable under air pressure to open said outlet.

5. In a torpedo, in combination with an air inlet pipe and a water and fuel vessel, an intervening air check valve comprising a casing having an inlet and outlets, cylindrical seat portions communicating with said outlets, and a valve plunger movable therein, having piston portions entering said seat portions in its closed position to close said outlets, said plunger movable under air pressure to open said outlets.

6. A torpedo air check valve according to claim 1, affording comparatively unrestricted passage to one outlet, and restricted passage to the other outlet.

7. A torpedo air check valve according to claim 5, having a constriction at its inlet to check the first inflow of air.

8. In a torpedo, in combination with an air inlet pipe and a water and fuel vessel, an intervening air check valve comprising a casing having an inlet and outlet, a valve plunger movable therein, normally closing said outlet and movable under air pressure to open said outlet, and a yielding stop for holding said plunger normally in the closed position, adapted upon entrance of pressure through such outlet to yield and permit the displacement of the valve plunger to discharge such pressure through the valve.

9. A torpedo air check valve according to claim 8, such stop comprising a spring-pressed plunger normally arresting the valve plunger in its closed position.

10. A torpedo air check valve according to claim 8, having a spring normally pressing the valve plunger to its closed position against said stop, and the latter having a stronger spring adapted to yield to a sufficient pressure entering through the outlet to permit the displacement of the valve plunger for discharging such pressure.

In witness whereof, I have hereunto signed my name.

WILLIAM DIETER.
